US00D933403S

(12) **United States Design Patent** (10) **Patent No.:** **US D933,403 S**
(45) **Date of Patent:** **** Oct. 19, 2021**

(54) **SHELF**

(71) Applicant: **Aluminum Architecture Institute Co., Ltd.**, Tokyo (JP)

(72) Inventor: **Naoto Fukasawa**, Tokyo (JP)

(73) Assignee: **ALUMINUM ARCHITECTURE INSTITUTE CO., LTD.**, Tokyo (JP)

(**) Term: **15 Years**

(21) Appl. No.: **35/509,102**

(22) Filed: **Sep. 25, 2019**

(80) **Hague Agreement Data**

Int. Filing Date: **Sep. 25, 2019**

Int. Reg. No.: **DM/207037**

Int. Reg. Date: **Sep. 25, 2019**

Int. Reg. Pub. Date: **Apr. 17, 2020**

(30) **Foreign Application Priority Data**

Mar. 26, 2019 (JP) 2019-006381

(51) **LOC (13) Cl.** **20-02**

(52) **U.S. Cl.**

USPC **D6/675.1**

(74) *Attorney, Agent, or Firm* — Manabu Kanesaka

(57) **CLAIM**

The ornamental design for a shelf, as shown and described.

DESCRIPTION

1. Shelf

1.1: Front View

1.2: Back View

1.3: Left Side View

1.4: Right Side View

1.5: Top View

1.6: Bottom View

1.7: Perspective View

1.8: Cross Sectional View taken from line A-A in figure 1.1

1.9: Cross Sectional View taken from line B-B in figure 1.1

1.10: Cross Sectional View taken from line C-C in figure 1.1

1.11: Enlarged Cross Sectional View taken from line D-D in figure 1.3

1.12: Enlarged Cross Sectional View taken from line E-E in figure 1.3

1.13: Enlarged Cross Sectional View taken from line F-F in figure 1.8

1.14: Enlarged Cross Sectional View taken from line G-G in figure 1.9

1.15: Enlarged Cross Sectional View taken from line H-H in figure 1.10

1.16: Enlarged Cross Sectional View taken from line I-I in figure 1.14

The broken lines depict the bounds of the claim and portions of the article that form no part of the claimed design.

1 Claim, 16 Drawing Sheets
